UNITED STATES PATENT OFFICE.

JOHN T. JANETTE, OF CHICAGO, ILLINOIS.

DESIGN FOR A CASING FOR AIR PUMPS AND FILTERS.

50,150.

Specification for Design.

Patented Jan. 9, 1917.

Application filed October 23, 1916. Serial No. 127,276. Term of patent 7 years.

To all whom it may concern:

Be it known that I, JOHN T. JANETTE, a citizen of the United States, residing at Chicago, in the county of Cook and State of Illinois, have invented a new, original, and ornamental Design for a Casing for Air Pumps and Filters, of which the following is a specification, reference being had to the accompanying drawing, forming a part thereof.

The figure shown in this drawing is a

side elevation of a casing for air pump and filter, showing my new design.

The base of this casing is made of opaque material and in the unique form shown, while the upper portion and the filter at the top are made of glass, which exposes the upper part of the base portion.

I claim:

The ornamental design for a casing for air pump and filter, as shown.

JOHN T. JANETTE.
